(57) **CLAIM**

The ornamental design for a roof ridge vent as shown and described.

DESCRIPTION

FIG. 1 is a top perspective view of a roof ridge vent embodying the new design;

FIG. 2 is a bottom perspective view thereof;

FIG. 3 is a top view thereof;

FIG. 4 is a bottom view thereof; and,

FIG. 5 is a side view thereof.

The figures show portions of the roof ridge vent in broken lines that do not form any part of the claimed design. The broken lines immediately adjacent to shaded surfaces depict the boundaries of the claim and form no part thereof.
